UNITED STATES PATENT OFFICE

JAMES H. EDWARDS, OF CHICAGO, ILLINOIS, ASSIGNOR TO PINES WINTERFRONT COMPANY, OF CHICAGO, ILLINOIS, A CORPORATION OF DELAWARE

THERMOSTATIC RADIATOR SHUTTER CONTROL

Application filed December 17, 1928. Serial No. 326,477.

The present invention relates to shutters for controlling the flow of air on internal combustion engines, and is particularly concerned with thermostatically controlled shutters.

The thermally responsive shutters of the prior art have been controlled by the temperature of the metallic parts of the engine or the temperature of the cooling water or other fluid employed, but there is generally a considerable time lag in the temperature effects which are produced in these parts by the variations in engine conditions. It may be a considerable time after the internal temperature of the engine has increased before the temperature of the water or the temperature of the engine block has raised appreciably, or enough to actuate a shutter device.

The temperature of the exhaust gases is however a fairly good indicia of the conditions existing inside the internal combustion engine, and furthermore any device responsive to the temperature of exhaust gases may be made to close automatically on the stopping of the engine, so that the heat will be retained as long as possible after the engine is stopped.

The present invention is of universal application to cooling systems having a liquid circulation system or to cooling systems in which the engine block is cooled directly by the flow of air against the engine or against heat conducting members carried by the engine, and the drawings merely illustrate one of the conventional cooling systems included within the scope of the invention.

One of the objects of my invention is to provide a thermally responsive radiator shutter control means which is extremely sensitive, and which will readily respond to varying conditions of engine operation.

Another object is to provide a thermally responsive radiator shutter control means, which will close the shutters within a short period of time after the engine ceases to operate.

Another object of the invention is the provision of a shutter controlling device, which is responsive to the temperature conditions actually existing in the combustion gases of

the internal combustion engine, and which is adapted to automatically close the shutters upon the stopping of the engine to retain all of the heat possible within the engine hood.

Another object of the invention is the provision of a heat responsive device of the class described, which is adapted to give long and satisfactory service without damaging the thermostatic wafers.

Other objects and advantages of my invention will be apparent from the following description and from the accompanying drawings, in which similar characters of reference indicate similar parts throughout the several views.

Referring to the drawings, of which there are two sheets,

Fig. 1 is a side elevational view, partly in section, showing my invention applied to an automobile engine;

Fig. 2 is an enlarged fragmentary vertical longitudinal sectional view, showing the method of mounting the thermally responsive shutter control means on an exhaust manifold;

Fig. 3 is an enlarged vertical cross-sectional view taken on the line 3-3 of Fig. 1, showing the thermally responsive shutter control means;

Fig. 4 is a top plan view taken on the line 4-4 of Fig. 5, partly broken away and partly in section, showing a modified form of a thermally responsive shutter control means;

Fig. 5 is a longitudinal vertical sectional view of the control means shown in Fig. 4.

Referring to Fig. 1, I have here illustrated one of the conventional forms of cooling systems including an internal combustion engine 10, an enclosure 11, a shutter controlled opening 12, shutters 13, and a fan 14. The present illustration includes the usual water cooling radiator 15, together with connections to the water jacket of the internal combustion engine 10, but I desire it to be understood that my invention includes the other conventional system of cooling engines in which a water cooling radiator is not employed, and in which the cooling air comes in direct contact with the engine or parts connected therewith.

The shutter mechanism, which has been diagrammatically illustrated, includes a supporting frame 16 together with a plurality of shutters 13 pivotally supported in the frame 16 on the trunnions 17 and adapted to close the opening 12 in the front of the engine enclosure. Each of the shutters 13 is usually provided with rearwardly extending flanges 18 pivotally connected to a shutter bar 19 and the shutter bar is adapted to simultaneously open or close a group of shutters.

The shutters 13 are normally urged to closed position by a spring 20, which may be attached to the shutter bar 19 and to the frame 15 16, urging the shutters in a clockwise direction in Fig. 1, and the radiator or shutter frame may pivotally support a bell-crank lever 22 having a pin and slot connection 23 to the shutter bar 19. The bell-crank lever 22 is 20 pivotally connected to a connecting rod 24 provided with a turnbuckle 25 for adjusting the effective length of the connecting rod and determining the point at which the shutters 13 will be actuated.

25 The opposite end of the connecting rod 24 may be pivotally connected to a second bell-crank 26, pivotally mounted on the casing 27 of a thermally responsive device, which is responsive to the temperature of the exhaust gases of the internal combustion engine 10.

In order that the wafers 28 may be responsive to the temperature of the exhaust gases rather than the temperature of the engine block, and in order that the wafers may not 35 be influenced by heat conducted from the engine block, I prefer to provide an insulated section 29 in the exhaust conduit 30, and the section 29 may consist of a short metal pipe having flanges 31 which are insulated from 40 flanges 32 on adjacent sections of the exhaust conduit 30 by heat insulating gaskets 33. The heat responsive device 27 may consist of a casing adapted to slidably support a plurality of wafers 28 in spaced relation to the exhaust conduit 30 in such manner that the wafers 28 are heated by radiation from the insulated section 29 of the exhaust conduit 30 rather than by conduction from adjacent parts. The casing 27 may be of any shape, 45 but in the present embodiment is substantially cylindrical and provided with a centrally located extension 34 adapted to house a spring 35 for maintaining the wafers 28 in proper position.

50 The housing 34 is provided with a bore 36 adapted to slidably receive a push rod 37 provided with a plate 38, and the spring 35 is confined between the end of the housing 34 and the plate 38, resiliently urging the wafers 28 against each other and against a supporting spider 39.

In order that the wafers 28 may be supported in spaced relation to the heated conduit section 29, I have provided the spider 39 which may be threaded into the casing 27

at 40, and the casing 27 is formed with downwardly extending walls 41 adapted to embrace the pipe section 29, and with laterally extending flanges 42 for securing the casing on the pipe section 29.

A relatively thick layer of heat insulating material, such as asbestos 43, is interposed between the casing 27 and the pipe section 29 at all points where these parts would otherwise come in contact, and the casing 27 may be secured upon the pipe section 29 by a pair of clamping metal straps 44, which should also be provided with a layer of heat insulation 45 interposed between the straps and the flanges 42. The stem 37 is provided with a pin and slot connection 46 to the arm 47 of the bell-crank 26, and the bell-crank 26 is pivotally mounted on the casing 27 upon an upwardly projecting lug 48.

In the embodiment shown in Figs. 4 and 5, the thermally responsive device is provided with a heat conducting member 49 adapted to project into the exhaust conduit 30, so that the exhaust gases impinge upon the heat conducting member 49 and the temperature of the heat conducting member will be substantially the same as the exhaust gases. In this embodiment, the casing 50 may be formed integrally with a short section 51 of the exhaust conduit 30, and the pipe section 51 is provided with flanges 52 which may be secured to flanges 53 on the conduit 30 by bolts 54.

A heat insulating gasket 55 is interposed between the flanges 52 and 53 and the bolts 54 may also be surrounded with heat insulation 56 and provided with a gasket 57 to prevent conduction of heat from the conduit 30 to the pipe section 51, of which the conducting member 49 is a part. The casing 50 may be substantially cylindrical and provided with an annular flange 58 adapted to support a similar flange 59 carried by an inner casing 60, and the inner casing 60 comprises a cup-shaped member having an annular flange 59 and adapted to be received in the casing 50 with its walls in spaced relation to the walls of the casing 50. The inner casing 60 is provided with a centrally located lug 61 for engaging the adjacent thermosetting wafer 28 at its center, which is the point of greatest expansion, and the casing 50 may be provided with a cover 62 for enclosing the wafers 28 and for slidably supporting the push rod 37.

The cover 62 is likewise provided with a centrally located spring housing 34 adapted to enclose a compression spring 35 and provided with a bore 36 for slidably receiving the push rod 37. The push rod 37 is provided with a wafer engaging plate 38 and the spring 35 is confined between the end of the spring housing 34 and the plate 38. The casing may also be provided with an upwardly extending lug 48 for pivotally sup-

porting a bell-crank 26 having a pin and slot connection 46 to the push rod 37, and the bell-crank is also provided with a pivotal connection to the connecting rod 24.

5 The operation of my invention is as follows: The shutters 13 are normally urged to closed position by the spring 20, and the wafers 28 are held against each other by the spring 35. In certain embodiments, the 10 spring 35 may be eliminated. The wafers 28 are normally contracted when the internal combustion engine is not running and the turbuckle 25 is so adjusted that although the engine may be running and the wafers 28 15 may be slightly heated and slightly expanded, the shutters are not opened until the temperature of the engine reaches a pre-determined point, preferably the temperature at which the engine operates most efficiently.

20 As the exhaust gases pass outward through the exhaust conduit 30, the pipe section 29 is heated by the exhaust gases and a portion of this heat is carried by radiation and by a limited amount of conduction and convection 25 to the wafers 28. As the temperature of the engine increases, the temperature of the exhaust gas discharged will also increase since the gases will not be cooled so much by contact with the surrounding engine parts, and 30 when the engine has reached a pre-determined temperature, any further increase of temperature of the exhaust gases will cause the wafers 28 to expand sufficiently to slightly open the shutters 13. Any great amount of 35 increase in the temperature of the exhaust gases will immediately affect the wafers 28 in such a manner that the shutters 13 are entirely opened and the cooling effect is increased before the water or engine block have 40 become hot enough to give the usual indications. In other words, the present device being responsive to the temperature of the exhaust gases, it is adapted to open the shutters whenever the engine is laboring under conditions 45 which increase the heating effect of the exhaust gases, and the present device may be actuated before the bad effects of increased heat of combustion have become evident in increased water heating or engine block heating.

The operation of the embodiment of Figs. 4 and 5 is substantially the same except that in this embodiment the pipe section in the exhaust conduit is provided with a heat conducting member against which the gas is impinged so that the heat conducting member 49 may follow more closely the temperature of the exhaust gases.

In this embodiment as well, the heat is carried to the wafers 28 principally by radiation across the dead air space between the casing 50 and the casing 60, so that the wafers 28 may not be excessively heated.

Upon the stopping of the engine 10, the 60 heated exhaust gases will no longer be dis-

charged through the conduit 30 and the shutters will be closed as soon as the wafers 28 have cooled sufficiently to contract a slight amount, after which the shutters will automatically retain within the hood 11 as much of the heat of the engine as is possible.

It will thus be observed that I have invented a novel radiator shutter control, in which the shutters are controlled by thermostatic members responsive to the temperature of the exhaust gases, and my radiator shutter control may be made to follow more closely the heat conditions within an internal combustion engine than the devices of the prior art which are responsive to the temperature of the engine block or the cooling water. My radiator shutter control is also adapted to close the shutters after the engine has stopped, to automatically prevent the escape of heat from the engine while the car is parked.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States, is:

1. A thermostat shutter control unit comprising a section of exhaust conduit for an internal combustion engine, said conduit being provided with a heat transfer chamber, a casing for thermostatic elements located in said heat transfer chamber, a plurality of thermostatic wafers located in said casing, a bell crank movably mounted upon said casing, a plunger slidably mounted in said casing for engaging said wafers, and a spring for maintaining said plunger in engagement with said wafers.

2. In a radiator shutter, the combination of an internal combustion engine having an exhaust conduit and cooling system, with a plurality of shutters for regulating the flow of air in said cooling system, a thermostatic unit for controlling said shutters, a section for the exhaust conduit thermally insulated from the exhaust conduit, a thermostat carried by said section and subjected to radiated heat from said section, and operative mechanical connections between said thermostat and shutters.

In witness whereof, I hereunto subscribe my name this 13th day of December, 1928.

JAMES H. EDWARDS.
